UNITED STATES PATENT OFFICE.

VOJTECH IHRISKY, OF BELA PRI VARIN, CZECHOSLOVAKIA.

TYPEWRITER.

Application filed November 29, 1926, Serial No. 151,526, and in Czechoslovakia June 9, 1925.

This invention relates to typewriters and has for its object to provide a pocket typewriter, with which journalists, reporters and the like, when journeying, at public meetings and the like may rapidly commit what they hear to paper, without being kept by the typewriter to one place. By means of the typewriter according to the invention they are given complete freedom of movement as regards the choice of their stance when taking down the reports. The only condition is that the person using the machine shall have both hands free.

The invention consists more particularly in this, that the alphabet is simplified and that a common sign is used for phonetically similar vowels or diphthongs, so that in any language 16 signs are found to suffice. With the aid of these 16 signs the reporter can then reproduce this report in full, as his memory will be assisted by the phonetic writing.

According to the invention only 16 phonetic signs are used which are distributed over two keyboards, such that each finger of each hand has two signs to manipulate. The keyboard carriers are so constructed that they may be easily held in the hand. The keys of the keyboards or the levers for the same transmit the movement of the keys to the writing part proper by means of Bowden wires and the like. The writing part of the pocket typewriter is made very small, so that it may be conveniently placed in a coat pocket. It is connected to the two keyboards as already stated by Bowden wires or push cables, which may be of any suitable length.

The accompanying drawings illustrate the invention,

Fig. 1 being a section through the writing part of the machine in front elevation,

Fig. 2 a cross-section through the writing part,

Fig. 3 a section through the operating mechanism of the writing part seen from the front,

Fig. 4 a section through one of the keyboards,

Fig. 5 a view from above on one of the keyboards in section,

Fig. 6 a detail of Fig. 4,

Fig. 7 a detail of Fig. 1,

Fig. 8 is a side view of the mechanism for rolling up and unrolling the ink ribbon,

Fig. 9 is a view from the front in section of Fig. 8,

Fig. 10 is a diagrammatic view of the type arrangement of the writing part, and

Fig. 11 an example of the distribution of the phonetic signs to the separate keyboards, letters being chosen in the present case as 60 phonetic signs.

The writing part of the pocket typewriter shall now be described with reference to the accompanying drawings. In the casing 1 (Figs. 1, 2 and 3), in the lower part thereof, on a shaft 38 two reels 9, 9' are mounted, which are kept at a certain distance apart by the pedestal 10. On these reels 9, 9' the paper band 8 on which the phonetic signs are written is rolled and unrolled. The paper band 8 is guided over guide rollers 4, 4' journaled in brackets 2, such that it always occupies correct position on the platen 5, which acts as the support, when writing. The paper band is always kept taut, so that it acts on the loose platen 5 in the manner of a driving belt. The paper band reel 9' is mounted loosely on the shaft 38, and is under the action of braking means 11, so that a certain application of force is required for turning it. The reel 9 is connected to the shaft 38 in such a manner that it is only slidably axially and must take part in the rotary motion of the shaft 38. The shaft 38 is driven by the driving mechanism housed in the casing 40.

The driving mechanism comprises a toothed wheel 45 having internal teeth, mounted on the shaft 72, and a driving spring 43 fixed to the said shaft and guided between discs 42. In the toothed wheel 45 there engages the pinion 46 which is mounted on the square part 38' of the shaft 38. By the square part 38' and the hub of the pinion 46 the shaft 38 is coupled with the driving mechanism. By winding up the spring 43 which acts like a clock spring the shaft 72 and with it the toothed wheel 45, 46 and the shaft 38 along with the drum 9 are caused to rotate, the rotary motion being rendered intermittent by a device to be described below.

In order to obtain a signal that the spring 43 is run down and that it is necessary for it to be rewound a special signalling device is provided in the casing 40. It consists of 105 a system of levers, which causes a signal bell

to sound. The system of levers operates as follows: The arm 60 of the two-armed lever 60' 61 rests against the spiral spring 43 and is kept pressed against the same by means 5 of the spring 59. When the spiral spring 43 is in the wound up state, the upward swing of the lever arm 60 will be greatest. The arm 61 is connected by means of a coupling member 62' to the pawl 61' which is 10 guided in a sleeve 62. Through the upward swing of the arm 60 the pawl 61' is moved out of reach of the teeth 68 of the toothed wheel 44. The toothed wheel 44 is fixed to the outer periphery of the internally toothed wheel 45 or is made integral with the same. 15 The sleeve 62 is rigidly connected to the two-armed lever 64, 69. The arc 64 is itself connected to a spring 65. The unsupported end of the lever 69 is provided with a clapper 70 which causes the bell 71 to sound. On the lever arm 60 being forced downwards through the spring 43 uncoiling, the lever arm 61 by means of the member 62' pushes the pawl 61' into engagement with the teeth 25 68 and is carried round when the ratchet wheel 44 is turned, until it slips off the tooth 68. Through the rocking motion of the pawl 61' the two-armed lever 64, 69 is rocked by means of the sleeve 62 and the spring 65 30 is loaded. On the pawl 61' being released by the tooth 68, the spring 65 moves the lever 69 in the direction towards the bell 71 and the clapper can cause the latter to sound. The movement of the lever 69 towards the bell 71 is limited by the stop member 63.

The motion of the ink ribbon is also derived from the driving mechanism in the casing 40. The rotary motion of the pinion 46 is transmitted from the hub 47 thereof by 40 means of a driving band or cord 48 to the hub 49 of the toothed wheel 52. The toothed wheel 52 is mounted on a lever 50 which is capable of rocking on the pin 51. According as the lever 50 is rocked by means of the 45 lug 53 projecting from the casing, either the ink ribbon reel 12 or 12' becomes operative as a driven member. The ink ribbon reels 12, 12' are coupled by means of the coupling parts 18, 18' to the toothed wheels 52, 57 or 50 their coupling parts 54, 54'. For making the ink ribbon reels reversible a toothed wheel 55 for instance is provided between the toothed wheel 52' and the toothed wheel 52 on the lever 50. 55 The ink ribbon reels 12, 12' are journalled in the arms 2' of the brackets 2 (see Figs. 8 and 9). In order to check whether there is still sufficient ribbon wound on the reel 12, a separate indicating arrangement is 60 provided. This arrangement consists of a two-armed lever 13', 15 which is mounted on the arbor 15' journalled in bearings in the brackets 2. On one end of the lever is mounted the roller 13 which rests against

the ink ribbon, the roller 13 being pressed 65 against the ribbon by the spring 14 which abuts against the fixed part 2' and acts on the other arm 15 of the lever. According as there is more or less ribbon wound on the reel 12 the lever 13' is rocked aside to a 70 greater or less extent. The rocking motion of the lever or the arbor 15' is transmitted by means of a band 17' to the pointer 17 which will thus swing more or less to the left or right and according to the position of 75 which, as observed through a window in the casing 1, not shown in the drawing, it is possible to see whether there is still sufficient ribbon on the reel 12.

Both the paper band 8 and the ink ribbon 80 must have an intermittent motion imparted to them. For this purpose another system of levers is provided, which is mounted on one of the brackets 2, see Fig. 1. The system of levers consists of the two-armed lever 19, 85 29 which is pivoted on the pin 39. This two-armed lever is always kept in an extreme position by the spring 30 which engages with the arm 29. The lever arm 19 is connected by means of a link 20 to the lever 21 which 90 lever is connected by the pin 21' to the three-armed lever 22, 23, 26' (see Fig. 7). The lever arm 23 strikes against the stop member 24 and thereby limits the throw of the lever arms 22 and 26'. At the ends of the lever arms 22 and 26' are inwardly projecting lugs 95 which engage in the teeth of the toothed wheel 6. In the lever arm 26' which is hollow there slides the plunger 25', on the end of which is the lug 25, the plunger being 100 kept pressed outwards by the spring 26. The stroke of the plunger is limited by the screw 28 which engages in the groove 27 of the plunger 25'.

On the lever arm 19 being forced inwards 105 in a manner to be described below, the lever arm 22 is also forced downwards by the link 20, the lever 21 and the pin 21' into one of the gaps between the teeth of the toothed wheel 6. By the same movement the lever 110 arm 26' is swung out of the gap between the teeth. This prevents the toothed wheel 6 being turned by the tension of the paper band 8, as the lug on the lever 22 holds one 115 of the teeth. On the tooth 7 being released by the lug 25, the latter will be forced by the spring 26 out of the arm 26', at least by the thickness of a tooth plus the thickness of the lug. Through the lug 25 lying above the tooth 7, when the lever 26' is rocked 120 aside, it becomes possible for the entire system of levers to return immediately into the position of rest, as, each time the system of levers returns, the lug 25 will engage in a gap between the teeth and, owing to the lug 25 being forced out, no tooth of the toothed wheel 6 prevents the lever from 125 rocking. The lever 22 with its hooked end

only acts as a detent for preventing the drum 5 from being turned more than a single step.

Owing to the fact, that through the arrangement just described the paper band can only travel forward intermittently, the reel 9 will also only be able to wind up intermittently and the driving spring 43 of the driving mechanism unloaded and the ink ribbon fed forward intermittently, as the ink ribbon reels are driven from the hub 47 of the pinion 46.

On the casing 1 the type container 36 is mounted. As will be seen from Figs. 1 and 10 the types are so arranged that four types can always strike the ribbon simultaneously. The types 33 are guided in guiding channel 35 in such a manner that, when operated, they strike the ribbon. As will be seen from Figs. 1 and 10 the middle four type guides are perpendicular to the ribbon, while the type guides of the laterally placed types are inclined to the horizontal, such that, on the types of the quadrant I being depressed, the types in the said quadrant will strike that part, where the middle type 33" strikes the ribbon. In the quadrants II, III, IV the arrangement is the same as in the quadrant I. The types are connected to pressure applying members 34, 34', 34" and so on, which in the present case may be rigid steel wires, the pressure applying members being connected through the cables or conduits 37, 37' to the keyboard, where they are connected to the corresponding levers of the keys.

The keys 72, 73 (see Figs. 4 to 6), by means of which the types 33 are operated, are mounted so as to rotate on the pins 77 in a casing 91. By depressing one of the keys, for instance the key 73, the two-armed lever 73' is rocked, the other end of which is provided with a pawl 76 which is rotatable about the pin 75 and has a small plate 74 on its upper side, which strikes against the adjustable stop member 88, causing the pawl 76 to rock, on the lever 73' moving upwards. The pawl 76 itself is kept pressed by the spring 94 into one of its extreme positions. A projection 93 on the pawl 76 engages with the projection 92 on the two-armed key lever which is mounted so as to rock on the pin 78 (see Fig. 6). On the lever 73', 73" being rocked, the key lever 79, which is carried along by the pawl 76 is also rocked, until the pawl 76 is turned by the stop member 88, so that the two lugs 92, 93 cease to engage, whereby the key lever 79 is liberated. On the key lever 79 moving downwards the pressure applying member 34 which is guided in the guide 35 is also moved and one of the types 33 (Fig. 1) is caused to strike the ribbon. Between the two levers 73' and 79 dampers 86 are provided. The lever 79 is connected by means of a pressure applying

bar 82' having a collar 82 to a spring 83 one end of which rests against a fixed stop 84 and the other end of which rests against the collar 82. On the key lever 79 being moved downwards, the spring 83 is compressed and throws the key lever 79 back into its initial position, as soon as the pawl 76 has released the same. On the lever 79 which has a recess 79" being depressed, the lever 81 which is pivoted on the pin 81' will also be 75 rocked, through the pin 80 which extends transversely under all the keys to the blank key being pressed downwards by the lever 79. By rocking the lever 81 the pressure applying member 32 is moved, which acts 80 on the lever 19 of the shift mechanism described above. Through the lever 19 being depressed by the pressure applying member 32, the intermittent forward feed of the ribbon is released. In order that the 85 feed motion of the ribbon shall not be released at the same time as the key is struck, the recess 79" must be made of a suitable depth, in order that the lever 81 shall be rocked slightly later than the type lever 79. If it 90 be desired to feed the ribbon forward without a type being written, it is only necessary to depress the blank key 87. The unsupported ends of the type actuated lever 79 are guided in a comb. 95

Each keyboard contains eight type keys, each of which corresponds to a sign. The co-ordination of the signs to the separate keys may for instance be that shown in the diagram in Fig. 11. The keyboard support 100 91 is so constructed that it can comfortably be taken into the hollow of the hand, the thumb being inserted in a gripping or holding member on the lower part of the keyboard carrier, which is not shown in the 105 drawing. The eight keys of each keyboard are only operated with the four fingers of the hand. Each finger operates two keys (72, 73).

Modifications in the arrangement of the 110 separate parts and in the construction may of course be made without departing from the spirit of the invention.

What I claim is:

1. A pocket typewriter comprising two 115 separate parts, the writing part and the operating part for operating the said writing part, the writing part having a plurality of type members, the operating part having a keyboard, a plurality of members for transmitting in their longitudinal direction the motion of the individual keys of the keyboard to the corresponding type members, ducts for guiding the said transmitting members and conduits for said members 120 forming the physical connection between the writing part and the operating part, as and for the purpose set forth. 125

2. A pocket typewriter comprising two 130 separate parts, the writing part and the

operating part for operating the said writing part, the writing part having a plurality of type members, the operating part having a key board, a plurality of members for transmitting in their longitudinal direction the motion of the individual keys of the keyboard to the corresponding type members, ducts for guiding the said transmitting members and conduits for said members forming the physical connection between the writing part and the operating part, as and for the purpose set forth.

3. A pocket typewriter comprising two separate parts, the writing part and the operating part for operating the said writing part, the writing part having a plurality of type members, one type member for each group of phonetically similar vowel sounds, the type members being arranged in a square formation, guides for the said type members, the four centrally positioned type members and guides being perpendicular to the writing surface and the type members and guides at the periphery of the square being at an angle to the four centrally positioned type members and guides, such that the type members around the periphery are capable of striking exactly the same place on the writing surface struck by one of the centrally positioned type members, the operating part having a key-board, a plurality of members for transmitting in their longitudinal direction the motion of the individual keys of the keyboard to the corresponding type members and ducts for guiding the said transmitting members and for physically connecting the writing part and the operating part, as and for the purpose set forth.

40. 4. A pocket typewriter comprising two separate parts, the writing part and the operating part for operating the said writing part, the writing part having a plurality of type members, one type member for each group of phonetically similar vowel sounds, the operating part having a keyboard, a plurality of striking levers corresponding to the number of type keys, a detent member pivoted on one end of each key of the keyboard for carrying along the striking lever, on the key being depressed, an adjustable stop member, a spring for returning the striking lever into its initial position, on the said lever being released by the detent member striking the adjustable stop member, a plurality of members for transmitting in their longitudinal direction the motion from the striking lever, when it is depressed, to the type members and ducts for guiding the said transmitting members, as set forth.

60. 5. A pocket typewriter comprising two separate parts, the writing part and the operating part for operating the said writing part, the writing part having a plurality of type members, one type member for each

group of phonetically similar vowel sounds, an ink ribbon and means for advancing the said ribbon intermittently, the operating part having a keyboard, a plurality of striking levers corresponding to the number of type keys, a detent member pivoted on one end of each key of the keyboard for carrying along the striking lever, on the key being depressed, an adjustable stop member, a spring for returning the striking lever into its initial position, on the said lever being released by the detent member striking the adjustable stop member, a plurality of members for transmitting in their longitudinal direction the motion of the individual keys of the keyboard to the corresponding type members, ducts for guiding the said transmitting members, a blank key for releasing the means for advancing the ink ribbon, so that it can advance by one step, a blank key lever and a stop member on the blank key lever capable of being struck by the striking lever near the end of its rocking motion for putting the blank key lever into operation, as set forth.

6. A pocket typewriter as claimed in claim 1 and having in the writing part a platen, a two-armed detent device, a ratchet wheel mounted coaxially with the platen and capable of coacting with the said detent device, a lever on the detent device, a two-armed lever, a link connecting one arm of the two-armed lever to the lever on the detent device, a spring always bearing against the other arm of the two-armed lever, means for depressing the former arm of the two-armed lever in opposition to the spring on the latter arm thereof for causing one arm of the detent to engage in the teeth of the ratchet wheel and lock the same and the other arm of the detent to be disengaged from the teeth of the ratchet wheel, a member having a hooked end, slidable in the said other arm of the detent device, a spring for pushing the slidable member outwards in the said arm, means for limiting the amount by which it is pushed out to the thickness of the hooked end and the thickness of a tooth of the ratchet wheel, such that, on the arm returning under the action of the spring bearing on the arm of the two-armed lever, the hooked end can engage between two teeth of the ratchet wheel before the other arm of the detent device releases the tooth with which it is in engagement, as set forth.

7. A pocket typewriter including a writing part and a keyboard for operating the same and having in the writing part, a shaft, two reels mounted on the shaft, one loosely, for receiving a paper band capable of being wound from the loose reel onto the other reel, a pinion on the shaft, a toothed wheel having an internal ring of teeth meshing with the said pinion, means for driving the said wheel, an ink ribbon, two brackets,

two reels journaled on the said two brackets, on which the ink ribbon is wound and operating means for the ink ribbon, comprising a train of gear wheels and a driving band running on the hub of the pinion for transmitting motion from the pinion to the said ink ribbon, as set forth.

8. A pocket typewriter including a writing part and a keyboard for operating the same and having in the writing part a shaft, two reels mounted on the shaft, one loosely, for receiving a paper band capable of being wound from the loose reel onto the other reel, a pinion on the shaft, a toothed wheel having an internal ring of teeth meshing with the said pinion, means for driving the said wheel, an ink ribbon, two brackets, two reels journaled on the said two brackets, on which the ink ribbon is wound, operating means for the ink ribbon, comprising a train of gear wheels and a driving band running on the hub of the pinion for transmitting

motion from the pinion to the said ink ribbon, a rocking lever supporting the gear wheel of the train of gear wheels, which is 25 driven by the driving band from the pinion, for enabling the said gear wheel to be caused to engage with either ink ribbon reel, as set forth.

9. A pocket typewriter including a writing part and a keyboard for operating the same and having in the writing part a shaft, two reels mounted on the shaft, one loosely, for receiving a paper band capable of being wound from the loose reel onto the other 35 reel, a pinion on the shaft, a toothed wheel having an internal ring of teeth meshing with the said pinion, a spring for driving the said wheel and an alarm device for notifying that the said spring has run down, as 40 set forth.

In testimony whereof I have signed my name to this specification.

VOJTECH IHRISKY.
